OIL BURNING APPARATUS AND METHOD

Application filed October 24, 1930. Serial No. 490,929.

This invention relates generally to apparatus and methods for the burning of oil fuel, such as are commonly utilized for domestic heating furnaces or for boiler installations.

5 In many oil burner installations it is necessary to operate the apparatus intermittently rather than continuously over long periods. For example when installed in domestic heating furnaces the apparatus is frequently jointly controlled by a clock and by a thermostat device. In such installations the apparatus is shut down for several hours during night time, and at a certain time in the morning determined by the setting of the 10 clock, the apparatus is started in operation, after which it operates under the control of the thermostat. It is evident that after the apparatus has been in operation for a considerable time, the parts in proximity to the 15 burner nozzle become heated to a substantial degree, thus materially heating the oil flowing to the nozzle. However after the apparatus has been at rest for several hours as during night time, all of the parts of the apparatus assume a relatively low temperature, 20 depending upon the temperature of the surrounding atmosphere, so that for a substantial interval following starting of the apparatus from such a period of rest, the oil fed to the burner nozzle is relatively cold. Such a fluctuation in the temperature of the oil being fed to the burner nozzle is generally not a detrimental factor when the apparatus 25 is being operated upon oil which is relatively light or which is not highly viscous. However if it is attempted to operate such apparatus on oil which is normally relatively viscous, commonly termed "heavy fuel oil", difficulty is encountered in maintaining a 30 properly controlled oil feed. Thus if the apparatus is started in operation when cold, the flow of highly viscous oil to the burner nozzle is reduced because of its resistance to flow. However after the apparatus has been 35 in operation for a time and the parts adjacent the nozzle have become warm, the oil being fed to the nozzle becomes heated in its flow, and thus the rate of feed tends to become greater. If the apparatus is adjusted 40 to give a proper combustible mixture after the parts have become warmed, the flow of oil to the nozzle when starting under cold conditions may be insufficient to permit proper ignition. On the other hand if the apparatus is adjusted to secure proper ignition under 45 cold conditions, then after the parts have become warmed the flow of oil increases to such an extent as to cause inefficient combustion. It has previously been proposed to alleviate this difficulty by the use of special metering means for regulating the feed of oil to the burner, but all of the metering means of which I am aware have been relatively complicated in construction, relatively expensive to manufacture, and required frequent servicing to maintain them in proper 50 operating condition.

It is an object of the present invention to devise an oil burning apparatus and method which will make practical the use of relatively heavy viscous fuel oil. The apparatus as described herein is relatively simple in construction and operation, and will operate satisfactorily over relatively long periods without requiring frequent servicing.

Further objects and features of the invention will appear from the following description in which the preferred embodiments of the invention have been set forth in detail in conjunction with the accompanying drawing. It is to be understood that the appended claims are to be accorded a range of equivalents consistent with the state of the prior art.

Referring to the drawing:

Figure 1 is a side elevational view illustrating diagrammatically apparatus incorporating the present invention.

Figs. 2, 3 and 4 are circuit diagrams for the electrical orifice heater.

The apparatus illustrated in the drawing consists generally of an oil burner 10 of the oil atomizing type, an oil supply means 11 which preferably functions to supply oil at a predetermined static pressure, and oil flow control means 12. As representative of a suitable burner I have shown a nozzle 13 extended thru the wall 14 of a heating furnace or boiler combustion chamber. When in operation a blast of air is delivered thru

nozzle 13 by a blower or fan, driven by suitable means such as an electric motor or steam turbine. A rotating atomizing cup 16 is disposed coaxially within nozzle 13 and oil is supplied to this cup thru a suitable pipe 17. When in operation oil delivered from pipe 17 is thrown from the lip of cup 16 in the form of a finely atomized spray which intermingles with the blast of air discharged thru nozzle 13, to form a combustible mixture. It is common practice with such burners to form the nozzle, the blower, and the driving motor or turbine as a structural unit, and pipe 17 extends from this unit to a suitable tail piece or fitting.

As previously explained the oil supply means 11 is preferably adapted to deliver oil at an automatically controlled static fluid pressure, and therefore in the method of the present invention it is representative of a source of oil normally at a sustained static fluid pressure. Structurally the specific means illustrated consists of a casing or chamber 21 having a lower wall 22 formed with a port 23. A valve seat 24 is formed in conjunction with port 23, and is adapted to cooperate with a movable valve member 26. For automatically effecting movements of valve member 26 a sylphon tube or equivalent means 27 is disposed within casing 21, the upper end of this tube being clamped to the upper end of casing 21 by the casing closure 28, while the lower end is secured to the valve member 26.

Valve member 26 is normally biased towards closed position, and in order to permit adjustment of this bias, a plug 29 is shown threaded into the casing closure 28. A screw 31 is threaded into plug 29, and the lower end of this screw is formed to engage the upper end of a compression spring 32. The lower end of spring 32 is seated upon the lower end of sylphon tube 27 so as to normally tend to urge this tube towards an extended position. By loosening nut 33 screw 31 can be adjusted so as to vary the tension upon spring 32, and thus vary the force with which valve member 26 is urged toward closed position.

For continuously introducing oil into casing 21 about the exterior of sylphon tube 27, during operation of the apparatus, I have indicated schematically a suitable oil pump 36. The outflow side of this pump is indicated as being connected with casing 21 by pipe 37, while the inflow side of the pump communicates with a suitable oil reservoir 38. Another suitable oil pump 39 has been indicated schematically, and this pump has its inflow side connected to an oil pipe line 41 and its outflow side discharging into reservoir 38. Pipe line 41 connects with a suitable oil storage tank. Generally it is preferable that pump 39 be of greater capacity than pump 36 and that both pumps be ca-

pable of normally pumping oil at a rate exceeding the normal rate of oil consumption of the burner 10. For convenience both pumps 36 and 39 can be driven from a common source of power, and in practice they are commonly driven by the same electric motor or turbine which drives the blower or fan of the burner 10. An overflow pipe 43 also communicates with reservoir 38, and this pipe serves to return excess oil from the reservoir back to the oil storage tank. It is evident that in some installations the reservoir 38, which can be termed an auxiliary reservoir, might be omitted. In this event only a single oil pump would deliver oil from the oil storage tank to the casing 21, while oil discharged thru port 23 would be returned to the oil storage tank.

Connection with the oil supply means 11 and the burner is established thru the pipe 44 which communicates with the interior of casing 21. Another pipe 47 communicates thru closure 28 with the interior of sylphon tube 27, for a purpose to be presently explained. It is evident that with oil pumps 36 and 39 operating at a continuous speed, oil will be continuously pumped from the storage tank to the reservoir 38, and an excess of oil from this reservoir will be continually returned to the storage tank thru pipe 43. Oil will also be continuously pumped from reservoir 38 and delivered into casing 21, and since the amount of oil so delivered is in excess of the amount continuously removed thru pipe 44, fluid pressure within casing 21, pressing upon the lower end of sylphon tube 27, tends to compress this tube and also spring 32, to lift valve member 26. Thus in starting pumps 36 and 39 in operation, the pressure within casing 21 will build up to a certain predetermined value, after which valve member 26 will be automatically opened to permit bypassing a certain amount of oil back into reservoir 38. The result of such operation is that the fluid pressure within casing 21 and the fluid pressure of oil delivered thru pipe 44 will be maintained above a given hydrostatic pressure. This pressure can of course be regulated by adjusting the position of screw 31.

The oil flow control or compensating means 12 has been indicated as comprising a body 51 made of suitable material having good heat conductivity, such as metal. One portion of the passageway 52 in body 51 is connected to fitting 18 by means of pipe 53, and another portion of this passageway is connected to oil pipe 44 as shown. An inner annular portion 54 is formed within body 51, and this portion serves to provide a restricted orifice 56 thru which oil flowing thru body 51 must pass. One desirable form of orifice 56 is to taper portion 54, whereby the inner annular orifice surface 57 is of restricted area. To provide suitable means for heating the

inner surface 57 of the orifice I prefer to employ an electrical heating element 58 which is normally disposed in good heat transferring relationship with respect to the 5 metal of body 51. This element 58 can be provided with the usual electrical terminals 59 and 61 for connecting the same to a suitable source of electrical current.

Suitable electrical connections for the 10 heating element 58 are indicated in Fig. 2. In this instance the element is provided with two resistances 62 and 63, the resistance 62 of which is connected directly across the electrical current supply lines 64 and 66. In 15 practice element 58 is constructed so that it will utilize a relatively small amount of electrical energy, say in the neighborhood of 40 watts, and in an ordinary domestic furnace heating systems this element can be permanently connected to the usual 110 volt alternating current supply lines. If a greater amount of heat is required, both resistances 20 62 and 63 may be connected in shunt across the lines 64 and 66.

25 Fig. 3 indicates optional connections which can be made to effect a decrease in the amount of heat supplied when the apparatus is started in operation. In this case resistance 63 is connected across line 64 and 66, while 30 resistance 62 is connected between line 64 and wire 67. Wire 67 and line 66 can be connected across the terminals of the electric motor 68, this motor being the one for driving the blower of the burner. Upon closing of 35 contacts represented by switch 69, motor 68 is started in operation and resistance 62 is cut out. Connections of this kind can be employed where the boiler or furnace room in which the burner is located is relatively 40 warm when the apparatus is in operation.

The circuit arrangement shown in Fig. 4 serves to automatically increase the heat supplied to the orifice during operation of the burner, and can be utilized when the furnace 45 or boiler room remains cold and is not warmed to an appreciable degree during operation of the burner. In this case terminal 59 is connected with line 66, and one of the terminals 61 is connected to line 64. The 50 other terminal 61 together with terminal 59 is connected across the terminals of the motor 68. Upon closing switch 69, to start the motor 68 of the burner, terminals 61 are connected together so that resistances 62 and 63 55 are connected in shunt across the current supply lines. For the majority of installations the circuit arrangement of Fig. 2 has been found to give the best results.

To explain the mode of operation of the 60 apparatus described above and the method utilized in the present invention, it will be presumed that circuit arrangements are employed as shown in Fig. 2. Thus when the apparatus is not in operation the inner surfaces of orifice 56 are always maintained at

an elevated temperature. Assuming now that the burner motor is started in operation and is accompanied by operation of the oil pumps 36 and 39, oil will be delivered from pump 36 into casing 21. Assuming that all of 70 the parts of the apparatus are relatively cold, the oil will be highly viscous, and in the absence of control or compensating means 12, an insufficient amount of oil would be supplied to the burner to effect proper ignition. 75

However in my apparatus as the highly viscous column of oil flows thru orifice 56, the outer periphery of this oil column is heated by the inner surfaces of this orifice thus substantially modifying its flow characteristics. When the column of oil has been treated in this manner in passing thru the heated orifice 56, it flows more nearly like an oil which is substantially less viscous, and is delivered by pipe 17 to the atomizing cup 16. After the apparatus has been in operation for a considerable period and the parts have become heated to a substantial degree, the body of the oil delivered by pump 36 also becomes heated and thereafter the control or compensating means 12 has little if any effect upon operation of the apparatus. 85

It will be noted from the above that the function and effect of control or compensating means 12, is to so affect the flow characteristics of highly viscous cold oil and to compensate for the tendency of the apparatus to deliver an insufficient amount of oil to the burner when started under cold conditions. In other words with my apparatus adjustment can be made to secure a good combustible mixture under normal running conditions when the parts are heated, and when it is so adjusted a sufficient amount of highly viscous oil will be supplied to the burner when starting under cold conditions, to effect proper ignition. 100

It has been found that more effective control or compensation can be effected by the means 12 if the starting differential pressure between the inflow and outflow sides of the orifice 56 is maintained substantially constant. This result is made possible by the use of the pipe connection 47 which connects between the outflow side of the orifice 56 and the interior of sylphon tube 27. Thus if the pressure in the outflow side of the orifice is relatively high, due to flow resistance thru the relatively small pipe 17, (a condition which is present when the apparatus is cold and the oil highly viscous), the static fluid pressure transmitted thru pipe 47 to the interior of the sylphon tube is correspondingly increased with the result that the bias tending to close valve member 26 is increased. Thus a greater fluid pressure is built up within casing or chamber 21 to increase the static fluid pressure upon the inflow side of the orifice. The converse effect takes place when the outflow pressure 110 115 120 125 130

on the orifice decreases, as the parts of the apparatus become heated sufficiently to heat the body of the oil. It is possible to operate the apparatus successfully without the 5 pipe connection 47 between the outflow side of the orifice and the interior of sylphon tube 27. However such a connection has been found desirable, since it makes possible better control of the oil flow to permit reliable 10 starting and continued operation after starting with a good combustible mixture.

The heated orifice which I utilize with my apparatus is not to be confused with auxiliary means for heating the body of oil supplied to 15 the burner. Such means require a relatively large amount of heat, and if electrical, require a relatively high electrical power consumption. My heated orifice operates with a minimum of power consumption, and functions only to heat a film of oil on the outer 20 surface of the oil column passing thru the same.

I claim:

1. In an oil burning apparatus, a burner 25 adapted to burn oil supplied to the same, a source of oil under pressure having a pipe connection with said burner, an orifice in said connection serving to restrict flow of oil to the burner, said orifice having surfaces 30 adapted to be heated to an elevated temperature, and means for heating the orifice.

2. In an oil burning apparatus, a burner adapted to burn oil supplied to the same, a source of oil normally at a substantially constant pressure having a pipe connection with the burner, and an orifice in said pipe connection serving to restrict flow of oil to the burner, said orifice having surfaces adapted to be heated to an elevated temperature, and 40 means for supplying heat to the orifice.

3. In an oil burning apparatus, a burner adapted to burn oil supplied to the same, a source of oil normally at a substantially constant pressure having a pipe connection with the burner, and an orifice in said pipe connection serving to restrict flow of oil to the burner, and means for supplying heat to the surfaces of said orifice.

4. A method of controlling flow of viscous 50 oil from a source to an oil burner comprising heating the outer surface of the oil column flowing to the burner from the source while immediately restricting the flowing column at the point of heating of the outer surface of the flowing column.

5. A method of controlling flow of viscous oil from a source to an oil burner comprising causing the oil from the source to flow thru a restricted orifice, and heating the surfaces 60 of the orifice in contact with the oil column flowing to the burner.

6. A method controlling flow of viscous oil from a source to an oil burner comprising causing the oil from the source to flow thru a restricted orifice supplying heat to the sur-

faces of the orifice in contact with the oil column flowing to the burner and maintaining the static fluid differential pressure between the inflow and outflow sides of the orifice substantially constant.

In testimony whereof, I have hereunto set my hand.
